UNITED STATES PATENT OFFICE.

CHARLES J. FANCHER, OF WINDSOR, VERMONT, AND ROBERT A. JOHNSON, OF LONG-MEADOW, MASSACHUSETTS, ASSIGNEES, BY MESNE ASSIGNMENTS, TO WOODWARD, HUBBARD COMPANY, OF HILL, NEW HAMPSHIRE, A CORPORATION OF NEW HAMPSHIRE.

BOXING MECHANISM.

Original application filed January 12, 1927, Serial No. 160,639. Divided and this application filed December 21, 1927. Serial No. 241,576.

Our invention relates to improvements in mechanism for packing small objects such as glaziers' points, in boxes, the same being a divisional part of our application for Letters 5 Patent of the United States, filed January 12, 1927, Serial No. 160,639.

The primary object of our invention is to produce semi-automatic mechanism for expeditiously introducing predetermined numbers of small objects and especially objects 10 such as glaziers' points, in boxes, wherein said objects or points are arranged compactly and evenly or orderly, and in condition for convenient removal when required for use. 15 Usually these objects, after being cut, are first formed into trains and heated with material which causes them to adhere to each other, and then cut into sticks each of a predetermined length and containing the required 20 number of objects.

The packing is performed automatically, except that the box is placed in its holder, moved into receiving position initially and after each layer or row of sticks of objects, 25 except the last row, is introduced therein, depressed after each of said rows is introduced, and removed by hand.

Another object is to provide means for automatically clamping and releasing the box 30 while in the holder, to enable the same to be moved forwardly and rearwardly therein.

A further object is to provide convenient means for manually raising and lowering the box as required during the loading operations. 35

Other objects and advantages will appear in the course of the following description.

A preferred embodiment of the invention, 40 whereby we attain the objects and secure the advantages of the same, is illustrated in the accompanying drawings, and we will proceed to describe the invention with reference to said drawings, although it is to be understood that the form, construction, arrangement, etc., of parts in various aspects are not material and may be modified without departing from the spirit of the invention.

In the drawings, in which like reference 45 characters designate like parts throughout the several views, Figure 1 is a rear elevation of the stand or frame which supports the slide and the rotary driving and the oscillatory operating elements of the boxing mech-

anism, and of said elements, some of which latter are in section, the view being taken on lines 1—1, looking in the direction of the associated arrow, in Fig. 3, and projected from said last-named view; Fig. 2, a longitudinal, vertical section through portions of the boxing mechanism, illustrating certain operations of the same; Fig. 3, a front side elevation of boxing mechanism which embodies a practical form of our invention as aforesaid; Fig. 4, a back side elevation of said mechanism; Fig. 5, a top plan of said mechanism, the same being projected from corresponding parts and members in Fig. 4; Fig. 6, a bottom plan of said mechanism, projected, as in Fig. 5, from Fig. 4; Fig. 7, a sectional detail, taken on lines 7—7, looking in the direction of the associated arrow, in Fig. 5; Fig. 8, an operative, back side elevation of the mechanism; Fig. 9, a sectional detail on lines 9—9, looking in the direction of the associated arrow, in Fig. 8, and, Fig. 10, an operative detail of certain parts of the mechanism.

Although we have illustrated our boxing mechanism as a part of a glazier's-point machine, it is to be understood that said mechanism can be applied to or used in connection with a machine or machines other than a glazier's-point machine.

This mechanism is designed at each cycle to handle and introduce into a box ten sticks 85 of objects or points, but said mechanism might be constructed to handle more or less than that number of sticks without making any material change in the construction, or at least, without affecting the invention.

It is assumed, for the purposes of this description, that each of the ten sticks consists of 100 glaziers' points which are temporarily united with each other by means of suitable adhesive material applied after the points 95 have been cut and during their progress through the glazier's-point machine, as hereinbefore explained, and that the sticks are cut off after said adhesive material is applied.

A frame 2 is mounted on and secured to a 100 support, as 3, which in the present case forms the table of the glazier's-point machine, at the left hand or rear end thereof. The main portion of the frame 2 is mounted directly on the table 3, and other parts of said frame extend beyond the rear end of said table. The

frame inclines a little toward the front end of the table, and is tilted toward the front of said table, in the present example. Extending from the frame at the bottom beyond the 5 rear end of the table, is an arm 4 in front and a brace 5 behind for said arm; and extending from said frame near the upper end in front, also beyond said rear end of the table, is an arm 6. A slide 8 is securely attached to the 10 outer terminals of the arms 4 and 6.

The slide 8 extends in the same general direction as does the table 3. The arms 4 and 6 support and hold the slide 8 at an inclination downwardly and rearwardly, longitudinally, and downwardly and forwardly, transversely. The inner end of the slide 8 is positioned transversely at an angle of 40°, and at the lower, outer end is horizontal. There are ten longitudinal channels 10 in the 20 slide.

It is to be observed that the slide 8, as illustrated in connection herewith, is somewhat conventionalized, inasmuch as actually the slide with its channels is curved from the 25 forty degrees at the inner end to the horizontal at the outer end.

At each cycle of the glazier's-point machine ten sticks of points, with 100 points in each stick, are delivered to the slide 8 at the upper, 30 forward or inner end.

Two brackets 11 are bolted to the frame 2 and extend over the rear end of the table 3, and the supporting arm 6, for the slide 8, is 35 adjustably bolted to the foremost of these brackets.

Secured to the back side of the rear upright of the frame 2 is a bracket 12 having a bearing 13; and the rear terminal of a shaft 14 is journaled in said bearing. Here the bearing 13 and the shaft 14 incline downwardly and rearwardly, hence a ball-bearing 15 is provided for said shaft at the inner end of said bearing, through the medium of which ball-bearing said shaft is prevented from moving in the direction of its length rearwardly in said bearing, but the means of prevention being of the anti-friction type does not materially interfere with the rotation of the shaft. Mounted on and secured to the 40 rear terminal of the shaft 14 is a worm 16. The worm 16 is contiguous with the outer end of the bearing 13. A transverse shaft 17 is journaled in bearings provided at the rear ends of a pair of arms 18 that extend outwardly from the frame 2, over the rear end of the table 3. The shaft 17 extends beyond the 45 frame 2 over the worm 16, and mounted on and secured to this extending part of said shaft is a worm-wheel 19 which intermeshes 50 with said worm. A cam 20 is mounted on and secured to the cam shaft 17 between the arms 18.

By gravity the ten sticks of points, which 55 have been deposited in the channels 10 in the slide 8, slide down until the leading ends of

said sticks arrive at a downwardly extending lip 21 at the rear side of a movable stop 22, said lip normally being against the rear ends of said channels. An arm 23 extends from the center of the top of the movable stop 22 70 towards the back side of the machine, and is rigidly secured at its outer end to the rear end of a plunger 24 mounted to slide and rock in two bearings 25 at the outer ends of two arms 26 bolted to the under side of the slide 8. 75 The stop 22 when in normal position extends across the top of the rear-end portion of the slide 8, with the lip 21 against the extreme back end of said slide, and the ends of two cross rods 27, with which said stop is provided, resting on a pair of tracks 28. The tracks 28 have their front ends secured to the top of the slide 8, and extend downwardly and rearwardly beyond said slide. The rods 27 project beyond both ends of the stop 22 to 80 bear and ride on the tracks 28. A sleeve 29 is mounted on the plunger 24 between the bearings 25, and is keyed to said plunger in order to enable the latter to slide in said sleeve, and also, when partially rotated, to 85 rock said sleeve with it—see Fig. 9. It follows, therefore, that, when the plunger 24 is moved longitudinally, it carries with it the stop 22, the rods 27 then riding on the tracks 28; and, when said plunger is rocked in one 90 direction, it swings said stop upwardly, through the medium of the arm 23 and the sleeve 29, and, when said plunger is rocked in the opposite direction, said stop is returned to its former position with said rods on said 95 tracks.

A curved lever 30 has its forward end pivotally connected at 31 with the frame 2, and is provided on the back side intermediate of the ends with a cam roll 32. A link 33 has its forward end pivotally connected at 34 with the upper, rear terminal of the lever 30, and its rear end pivotally connected at 35 with the forward end of the plunger 24. Secured to the back side of the cam 20 are two cam plates 36 and 37 which form between them a cam-groove 38 for the roll 32. As the lever 30 is operated by the roll 32 in the cam-groove 38, at each revolution of the cam 20, the link 33 is caused to impart a rearward and forward movement to the plunger 24, and through said plunger and the arm 23 to the stop 22. The dwell in the cam-groove 38 is such that the stop 22 is retained in retracted position during about one-half of the revolution of the 100 cam.

A bent rod 39 extends radially from the under side of the sleeve 29, and then towards the front side of the machine or mechanism to have its free terminal received in a notch 40 105 in the rear terminal of a lever 41.

The lever 41 at its inner end is mounted on the same pivot or pivot rod 31 with the lever 30, and said first-named lever is provided with a roll 42 which is in the path of a segmental 110

cam-plate 43 secured to the front side of the cam 20.

At each revolution of the cam 20, and while the cam-plates 36 and 37 are causing the stop 22 to be reciprocated and said stop is at the end of its rearward travel, the cam-plate 43 encounters the roll 42 and rocks the arm 41 upwardly on the pivot or rod 31, and said arm carries with it the connected terminal of the arm 39 and rocks the sleeve 29 and the plunger 24, with the result that the arm 23 is swung upwardly with said plunger and raise said stop into the position shown in Fig. 8. As soon as the cam-plate 43 passes beyond the roll 42, the lever 41 rocks downwardly again, and, through the medium of the arm 39, imparts a partial revolution in the opposite direction to the sleeve 29 and the plunger 24, whereby the stop 22 is swung downwardly again until the rods 27 rest on the tracks 28. The arm 23 has a pivotal connection at 44 with the stop 22, and the tracks 28 at their rear terminals are slightly elevated, as shown at 45, thus enabling and causing the back side 25 of said stop to be raised, or said stop to be tilted upwardly from the lower to the upper longitudinal edges thereof, when said stop is moved into its rearmost position, so that said stop can interpose no obstruction to the sticks 30 of points, as 46, as they slide under the stop— see Fig. 2.

A support in the form of a shallow trough 47 is rigidly secured at its inner end to the outer end of the slide 8, and this trough receives the sticks as they slide down with the stop 22, and after said stop releases said sticks they continue to slide until they encounter a gate 48. The end of the trough 47 which is in contact with the slide 8 corresponds in width with the combined width of the channels 10 at their rear ends, but said sides converge toward the opposite end of said trough, so as to cause the sticks as they slide down in said trough, to come together 40 and close the spaces made by the channel partitions of the slide.

The gate 48 is a thin plate that extends across the trough 47, and the upper end of said gate is clamped to the rear end of an arm 49 which extends rearwardly from the horizontal part of a U-shaped rocker 50 mounted on and extending above the slide 8. One downwardly extending arm of the rocker 50 is pivotally connected at 51 with the back side of the slide 8, and the other downwardly extending arm of said rocker is rigidly attached to the upper part of a curved arm 52 which is pivotally connected at 53 with said slide diametrically opposite to the pivot 51. The arm 52 extends downwardly and forwardly, and has at the forward end a pin 54 which is received in a slot 55 in the free end of a lever 56. The lever 56 at the forward end is pivotally connected at 57 with the frame 2, below the rod 31, and said lever is provided with

a roll 58 which is in the path of a portion of the outer edge of the cam-plate 37 that assists in forming the high part of the cam-groove 38, such part being indicated at 59. Normally the gate 48 rests on the trough 47 near the rear end thereof, and at such time the roll 58 is out of contact with the cam-plate 37, but when the cam edge 59 of said cam-plate encounters said roll, the lever 56 is rocked downwardly on the pivot 57, imparts a downward movement to the arm 52, and thus rocks said arm and the rocker 50 on the pivots 51 and 53 forwardly, and causes the arm 49 and said gate to be raised into the position shown in Fig. 8.

The lever 41 is yieldingly held in its downward position by means of a spring 60 having the upper end attached to said lever and the lower end attached to the brace 5, and the lever 56 is yieldingly retained in its elevated position by means of a spring 61 having the upper end attached to the frame 2 and the lower end attached to said last-named lever.

A rod 62 is arranged to reciprocate in two bearings 63 forming parts of the arms 26, and locating said rod under the plunger 24, and said rod is in position to intercept the long arm of the angular rod 39 in the downward movement of said arm, and thus to afford a stop therefor and for the lever 41.

Rigidly attached to the inner end of the rod 62 is a dog 64 which is in the path of the forward end of the plunger 24, and rigidly attached to the outer end of said rod is a dog 65 having at the upper terminal a screw 66 which is in the path of the rear end of said plunger. An angular or L-shaped bar forms a pusher 67 which at one end is rigidly attached to the rod 62 a short distance from the dog 65. One arm of the pusher 67 extends across to the vertical plane of the longitudinal center of, but under, the trough 47, and the other arm of said pusher extends from the inner end of said first-named arm towards the rear end of said trough, as best shown in Fig. 105 6. Depending from the transverse arm of the pusher 67 is a pin 68. A bar 69 has its forward end secured to the under side of the slide 8 and extends rearwardly beneath the pusher 67 to assist in supporting and guiding the same.

The plunger 24, as it approaches the end of its rearward travel, encounters the screw 66 and thereby actuates the rod 62 in the same direction, carrying with the rod the pusher 67, and, as said plunger approaches the end of its forward travel, it encounters the dog 64 and actuates said rod with said pusher in the same direction.

Extending rearwardly from a lug 70 depending from the slide 8 near the upper, forward end thereof, and pivotally connected at 71 with said lug, is a box-holder arm 72, having at its rear terminal a raised, splayed part or support 73. Secured to the top of the

support 73 is a box holder comprising a bottom plate 74, and two side pieces 75 and 76, respectively, and an upwardly extending lip 77 at the rear end. The plate 74 has a central, longitudinal slot 78 therein which opens through the front edge thereof to accommodate the pusher 67, and the support 73 is correspondingly slotted. The side piece 75, which is on the front, is rigidly attached to the top of the plate 74, but the side piece 76 which is on the back, is pivotally connected at 79 with said plate, and has at the front end a downwardly and forwardly extending finger 80 the rear edge of which is beveled as shown in Fig. 5. The beveled edge of this finger is in the path of the pin 68. Depending from the under side of the plate or bottom 74, adjacent to the front edge of said bottom, and depending from the side piece 76, are two pins 81, and having its opposite ends attached to said pins is a spring 82. A notch 83 is cut in the back side of the bottom 74 to receive and accommodate the pin 81 in the movable side piece 76. Normally the spring 82 retains the pin 81 in the notch 83 against the inner edge of said notch, and the side piece 76 is thus held in clamped relation with a box, such as that represented at 84, which the bottom 74 is adapted to receive between the two side pieces and against the lip 77. At the end of the rearward movement of the rod 62, which movement is imparted to said rod by the plunger 24 through the medium of the screw 66 and the dog 65, the pin 68 contacts with the finger 80, and swings the side piece 76 on its pivot 79, against the resiliency of the spring 82, in the direction to carry outwardly the part of said side piece that engages the box 84, thus releasing said box. Upon the retraction of the rod 62, when the plunger 24 contacts with the dog 64, the pin 68 passes away from the finger 80, and the spring 82 acts to draw the movable side piece inwardly at its rear end and into contact with the box, thus compressing the box between the two side pieces and holding it in place on and in the holder. The notch 83 in the bottom 74 is deep enough to enable the side piece 76 to engage the box before the pin 81 contacts with the inner edge or end of said notch.

The box 84 has an articulated side 85 which when opened is permitted to assume the position shown, and to remain in that position during the loading operation or while the box is being filled with sticks of points. Thus it is seen that the box, when in position in the holder, is or should be open at the top as well as at the front end.

60 A stirrup 86, through which the box-holder arm 72 extends, depends from the slide 8 near the lower, rear end thereof to limit the downward movement of said arm on its pivot 71.

65 Pivottally connected at 87 with the front

side of the arm 72 is a height-control latch 88 to regulate the height or distance of said arm above the bottom of the stirrup 86, or the distance, which must be changed, between the support 73 and the plane of the fixed 70 stick-supporting member, and to provide five stops for the swinging movement of said arm, which stops are commensurate with the five rows of sticks and the four separators packed in a box, the distance between any two 75 adjacent stops being equal to the thickness of any of said rows and a separator. To this end the front edge of the lever 88, above the pivot 87, is cut to form five teeth 89, and a fixed lug or dog 90 is provided on the adjacent side of the slide 8 to be engaged by said teeth. Projecting from the same side of the slide 8 with the dog 90 is a stop pin 91, the head of the latch 88 being between said dog and pin, with the teeth 89 on the 80 lug side or edge of the latch. In Fig. 3 the upper tooth 89 of the latch 88 is in engagement with the lug 90 and the arm 72 thus positioned at its lowest point, except when said arm is permitted to rest on the stirrup 90 86, the aforesaid tooth then being out of engagement with said lug. In Fig. 2 the third tooth 89 from the bottom is in engagement with the lug 90, and the arm 72 is thereby positioned within two teeth of the highest 95 point at which it can be supported by said teeth and lug. The bottom of the stirrup 86 might take the place of what is now the fifth or bottommost tooth 89.

The pitch of all of the supporting parts 100 and members for the sticks is steep enough to cause said sticks to slide down by gravity into the box, unless and except when intercepted by the stop and gate.

In practice, the operator first places the 105 box 84 in the holder at the free end of the arm 72. This is done by inserting the box between the side pieces 75 and 76, and pushing said box forward on the bottom 74, with the box bottom under the trough 47, until the rear 110 end of the box encounters the rear end of said trough. The box is now in the position shown in Fig. 2. Then the operator raises the arm 72 at the free end and swings said arm upwardly from the bottom of the stirrup 86, 115 whereon said arm was resting, and engages the bottom notch 89 with the dog 90. Meanwhile ten sticks of points have slid down the channels 10 in the slide 8, under the movable guide 22, into contact with the lip 21, said stop with said sticks moves rearwardly, the sticks sliding from said channels into the trough 47, said stop is elevated and releases said sticks which continue to slide down in said trough until they contact with the gate 120 48; said gate is raised, and the sticks still in the trough move by gravity against the back end of the box. The operator has, of course, located the box in loading position before the gate 48 is elevated. Next the pusher 67 125 130

is automatically actuated against the front edge of the bottom of the box, and moves said box rearwardly against the lip 77, the ten sticks then sliding out of the trough onto said box bottom. The operator now rocks the latch 88 against the stop 91, swings the arm 72 down onto the bottom of the stirrup 86, places a pasteboard separator on top of the ten rows of sticks in the box, raises said arm, 10 engages the next tooth 89 above with the dog 90, and pushes the box forward until the back end of the box again strikes the back end of the trough. This time the rear-end portion of the trough 47 is directly above the afore- 15 said separator, instead of being directly above the bottom of the box as in the first instance. Just before the end of the first cycle, or by the time the box is pushed into the holder against the trough 47, the movable side piece 20 76 is released to the spring 82 and caused to clamp the box in place, said side piece having been actuated to open the way for the box at the time the pusher acted to move the box back to receive entirely therein the first row 25 of sticks. The box is clamped between the side pieces during the time the operator lowers the box holder, inserts the separator, raises said holder, and pushes said box forward and upward. These manual and automatic 30 operations are repeated without other change than to manipulate the latch 88 and the arm 72, each time the box is moved back in its holder and clamped in position, to lower the box for the reception therein of the suc- 35 ceeding row of sticks and the next separator, until, in the present example, five rows of sticks have been packed in the box, with four separators between. Finally the full box is taken from the holder, to be replaced by an 40 empty box, when the loading or filling operations are repeated.

Each succeeding row of sticks, after the first, slides from the trough 47 onto a separator, in Fig. 2, a separator is shown between the two rows of sticks 46 that have already been placed in the box, and another separator above the second row of sticks, at 92. The third row of sticks is about to be carried down with the stop 22 preparatory to being placed 45 in the box on top of the upper separator 92, in this view.

The movable stop 22, when down with its supporting rods 27 on the tracks 28, is retracted until the lip 21 is against the rear end of 50 the slide 8, and the gate 48 is lowered onto the trough 47, by means of the cam plates 36 and 37 and the mechanism operated thereby. The stop 22 when actuated downwardly and rearwardly, carries with it a load of ten sticks of points and deposits said load against the gate 48. The gate 48 remains down until the stop 22 is raised to release the sticks and returns to its foremost position to receive the next load of ten sticks. The operator then 55 pushes the box up under the end of the trough 60 65 70 75 80 85 90 95 100 105 110 115 120 125 130

47, and, as the stop 22 descends with the second load of sticks, the gate 48 is raised and the lip 21 in conjunction with the pusher 67 pushes the box off from the end of said trough, and the first load of sticks with it. Usually 70 the sticks follow down by gravity with the box, but should they stick the lip 21 pushes them along. The gate drops quickly, the stop 22 lifts and deposits its load against said gate, and the latter remains down to hold the 75 sticks while the operator returns the box after putting in a spacer. Thus it is seen that the gate 48 does not lift to release the sticks until the stop 22 descends with another load, and the load of sticks brought down by said stop 80 does not go into the box until the stop de- scends the next time. Actually, however, the sticks are in the box as soon as the operator pushes the box up under the trough, so that all that remains to do is to push the box away 85 from the trough and with it the sticks, said sticks being pushed from the trough by the stop 22 when it comes down with another load, the gate lifting just in time to permit the sticks to go with the box. The stop 22 is car- 90 ried down and with it the sticks retarded by the lip 21, until said stop is elevated by means of the cam plate 43 and the mechanism operated thereby. The sticks pass directly into the trough 47 from the slide 8. The rod 62, 95 when moved downwardly and rearwardly by the plunger 24, actuates the pusher 67 against the front edge of the bottom of the box and the box is moved down against the lip 77. Near the beginning of the downward and rearward movement of the pusher 67, or before said pusher contacts with the box or its contents, the pin 68 contacts with the finger 80 and swings the movable side 76 in the direction to make free or open the way for the 100 box between said side and the fixed side 75. During the return movement of the pusher 67, the pin 68 passes clear of the finger 80 and the spring 82 is permitted to draw the side 76 against the box and thus hold the lat- 105 ter in place. The pusher 67, after moving the box 84 back to the lip 77 the first time, when said pusher bears against the bottom of said box, bears against the sticks in the box at each succeeding rearward stroke until four 110 have been made, or five strokes in all, be- cause, after the first rearward stroke, the box is indexed and said bottom is no longer in the path of the pusher.

The rod 62 is made longer than the plunger 24, and arranged to remain idle during a portion of the stroke in each direction of said plunger, in order that there shall be sufficient time for the pusher 67 and the side piece 76 to be operated while the movable 115 stop 22 is being operated.

The pin 68 and the finger 80 must be so proportioned that the latter is in the path of the former at whatever elevation the box holder may be located by indexing.

Necessarily the sticks must be fed to the stop 22 at a rate which enables said stop to take care of them.

We claim:

5. In boxing mechanism, an inclined slide for the objects to be boxed, a support for said objects after they leave said slide, a movable stop to control said objects at the lower end of and beyond said slide, and permit them 10 to move down on to said support, means to cause said stop to release said objects, a box holder, and means to move a box in said holder away from said support and permit the objects to drop into said box.
15. 2. In boxing mechanism, an inclined slide for the objects to be boxed, a support for said objects after they leave said slide, a movable stop to control said objects at the lower end of and beyond said slide, and permit them 20 to move down on to said support, means to cause said stop to release said objects, a gate to check said objects after they are released by said stop, a box holder, means to move said gate from the path of said objects and permit 25 them to slide against the back side of a box in said holder, and means to move said box away from said support and permit the objects to drop into the box.
30. 3. In boxing mechanism, an inclined slide for a stick of objects to be boxed, a support for said stick after it leaves said slide, a movable stop to control said stick at the lower end of and beyond said slide, and permit it to move down on to said support, means to cause 35 said stop to release said stick, a box holder, means to move a box in said holder away from said support and permit the stick to drop into said box, a movable supporting arm for said holder, and means to position said arm at distances from said support which 40 vary according to the sticks to be placed in the box one on top of the other.
45. 4. In boxing mechanism, an inclined slide for a stick of objects to be boxed, a support for said stick after it leaves said slide, a movable stop to control said stick at the lower end of and beyond said slide, and permit it to move 50 down on to said support, means to cause said stop to release said stick, a gate to check said stick after being released from said stop, a box holder, means to move said gate from the path of said stick and permit the stick to slide against the back side of a box in said holder, means to move said box away from said 55 support and permit the stick to drop into the box, a movable supporting arm for said holder, and means to position said arm at distances from said support which 60 vary according to the sticks to be placed in the box one on top of the other.
55. 5. In boxing mechanism, an inclined slide for a stick of objects to be boxed, a support for said stick after it leaves said slide, a movable stop to receive said stick at the lower end of and beyond said slide, and permit it to move 65

down on to said support, means to cause said stop to release said stick, a box holder provided with a box-clamping member, operating means for said last-named member, means to move a box in said holder away from said support back in said holder, to permit the stick to drop into said box, a movable supporting arm for said holder, and means to position said arm at distances from said support which vary according to the sticks to be placed in the box one on top of the other. 75

6. In boxing mechanism, an inclined slide for a stick of objects to be boxed, a support for said stick after it leaves said slide, a movable stop to receive said stick at the lower end of and beyond said slide, and permit it to move 80 down on to said support, means to cause said stop to release said stick, a gate to stop said stick after it is released from said stop, a box holder provided with a box-clamping member, operating means for said last-named member, means to move said gate from the path of said stick and permit the stick to slide against the back side of a box in said holder, means to move said box away from said support back in said holder, to permit the stick to drop into the box, a movable supporting arm for said holder, and means to position 85 said arm at distances from said support which vary according to the sticks to be placed in the box one on top of the other. 90

7. In boxing mechanism, an inclined slide for the objects to be boxed, a movable stop for the objects on said slide, a support for said objects after they leave said slide, means to locate a box in operative position relative 100 to said support, a pusher adapted to move said box away from said support to permit said objects to drop into said box, and operating mechanisms for said movable stop, and said pusher, said operating mechanisms being timed to operate said stop to permit the objects to move onto said support, release them, and be returned to initial position, and to cause said pusher to move the box and be returned to initial position, at each cycle. 105

8. In boxing mechanism, an inclined slide for the objects to be boxed, a movable stop for said objects, a support for said objects after they leave said slide, a gate above said support back of said stop, means to locate a box in operative position relative to said support, and operating mechanisms for said movable stop, and said gate, said operating mechanisms being timed to operate said stop to permit the objects on said slide to move onto said support, release them, and be returned to initial position, and to move said gate out of the path of said objects and back into said path, at each cycle. 115

9. In boxing mechanism, an inclined slide for the objects to be boxed, a movable stop for said objects, a support for said objects after they leave said slide, a gate above said support back of said stop, means to locate a 120 130

box in operative position relative to said support, a pusher adapted to move said box away from said support to permit said objects to drop into said box, and operating mechanisms for said movable stop, said gate, and said pusher, said operating mechanisms being timed to operate said stop to permit the objects on said slide to move onto said support, release them, and be returned to initial position, to move said gate out of the path of said points, and back into said path, and to cause said pusher to move the box and be returned to initial position, at each cycle.

10. In boxing mechanism, an inclined slide for the objects to be boxed, a movable stop for said objects, a support for said objects after they leave said slide, means to locate a box in operative position relative to said support, said box-locating means including a movable clamping member, a pusher adapted to move said box away from said support to permit said objects to drop into the box, and operating mechanisms for said movable stop, said clamping member, and said pusher, said operating mechanisms being timed to operate said stop to permit the objects on said slide to move onto said support, release them, and be returned to initial position, and to cause said pusher to move the box and be restored to initial position, and said clamping member to be operated to open the way for the box and then to clamp the same, at each cycle.

11. In boxing mechanism, an inclined slide for the objects to be boxed, a movable stop for said objects, a support for said objects after they leave said slide, a gate above said support back of said stop, means to locate a box in operative position relative to said support, said box-locating means consisting in part of a movable clamping member, a pusher adapted to move said box away from said support to permit said points to drop into said box, and operating mechanisms for said movable stop, said gate, and said pusher and clamping member, said operating mechanisms being timed to operate said stop to permit the objects on said slide to move onto said support, release them, and be returned to initial position, to move said gate out of the path of said objects and back into said path, and to cause said pusher to move the box and be returned to initial position, and said clamping member to be operated to open the way for the box and then to clamp the same, at each cycle.

12. In boxing mechanism, an inclined slide, an inclined support at the lower end of said slide, a reciprocating and oscillating member to control the movement of objects from said slide onto said support, a box holder, a reciprocating pusher for a box in said holder, and operating mechanism, for said member and said pusher, timed to actuate the member to release the objects and return the member to initial position, and meanwhile actuate said

pusher to move the box and permit the objects to drop from said support into the box, and return the pusher to initial position.

13. In boxing mechanism, an inclined slide, an inclined support at the lower end of said slide, a reciprocating and oscillating member to control the movement of objects from said slide onto said support, an oscillatory gate adapted to stop the objects on said support after being released by said member, a box holder, a reciprocating pusher for a box in said holder, and operating mechanism, for said member, said gate, and said pusher, timed to actuate the member to release the points while the gate is in operative position, and subsequently to move said member to initial position and oscillate said gate, and, after said gate is moved to release the objects, to actuate said pusher to move the box and permit the objects to drop from said support into the box, and return the pusher to initial position.

14. In boxing mechanism, an inclined slide, an inclined support at the lower end of said slide, a reciprocating and oscillating member to control the movement of objects from said slide onto said support, a box holder provided with a spring-pressed clamping member, a reciprocating pusher for a box in said holder, and operating mechanism, for said member, and said pusher and clamping member, timed to actuate said first-named member to release the objects and return the member to initial position, and meanwhile actuate said clamping member and said pusher, to open the way for the box, and to move the box and permit the objects to drop from said support into the same, and release the clamping member to its spring and return the pusher to initial position.

15. In boxing mechanism, an inclined slide, an inclined support at the lower end of said slide, a reciprocating and oscillating member to control the movement of objects from said slide onto said support, an oscillatory gate adapted to stop the objects on said support after being released by said member, a box holder provided with a spring-pressed clamping member, a reciprocating pusher for a box in said holder, and operating mechanism, for said first-named member, said gate, and said pusher and clamping member, timed to actuate said first-named member to release the objects while the gate is in operative position, and subsequently to move said member to initial position and oscillate said gate, and, after said gate is moved to release the objects, to actuate said clamping member to open the way and said pusher to move the box and permit the objects to drop from said support into the box, and release said clamping member to its spring and return the pusher to initial position.

16. In boxing mechanism, a cam shaft, means to drive said shaft, an inclined slide

fixed in place, an inclined support at the lower end of said slide, a movable stop to control the movement of objects from said slide onto said support, means to operate said stop, a 5 box holder, means to elevate and depress said holder, a pusher for a box in said holder, means to operate said pusher, and members on said shaft to actuate the operating means respectively for said stop, and said pusher.

10 17. In boxing mechanism, a cam shaft, means to drive said shaft, an inclined slide, an inclined support at the lower end of said slide, a stop to control the movement of objects from said slide onto said support, means 15 to reciprocate said stop, means to oscillate said stop, a box holder, a pusher for a box in said holder, operating means for said pusher, and members on said shaft to actuate the reciprocating means for said stop, the oscillating means for said stop, and the operating means for said pusher.

18. In boxing mechanism, a cam shaft, means to drive said shaft, an inclined slide, an inclined support at the lower end of said slide, a movable stop to control the movement of objects from said slide onto said support, means to operate said stop, a gate to control the movement of said objects on said support, means to operate said gate, a box holder, a 30 pusher for a box in said holder, means to operate said pusher, and members on said shaft to actuate the operating means respectively for said stop, said gate, and said pusher.

35 19. In boxing mechanism, a cam shaft, means to drive said shaft, an inclined slide, an inclined support at the lower end of said slide, a stop to control the movement of objects from said slide onto said support, operating means for said stop, a box holder provided with a clamping member, a pusher for a box in said holder, operating means for said clamping member and pusher, and members on said shaft to actuate the operating 45 means respectively for said stop, and said clamping member and pusher.

20. In boxing mechanism, a cam shaft, means to drive said shaft, an inclined slide, an inclined support at the lower end of said slide, a reciprocating and oscillating stop to control the movement of objects from said slide onto said support, means to reciprocate said stop, means to oscillate said stop, a box holder provided with a clamping member, a 50 pusher for a box in said holder, operating means for said clamping member and said pusher, and members on said shaft to actuate the reciprocating means for said stop, the oscillating means for said stop, and the 55 operating means for said clamping member and said pusher.

21. In boxing mechanism, a cam shaft, means to drive said shaft, an inclined slide, an inclined support at the lower end of said 60 slide, a stop to control the movement of ob-

jects from said slide onto said support, operating means for said stop, a gate to control the movement of said objects on said support, operating means for said gate, a box holder provided with a clamping member, a pusher 70 for a box in said holder, means to operate said clamping member and said pusher, and members on said shaft to actuate the operating means respectively for said stop, said gate, and said clamping member and pusher. 75

22. In boxing mechanism, a slide provided with bearings, a support at the lower end of said slide, a plunger in said bearings, an arm secured to said plunger, a stop connected with said arm and having a lip which extends down back of said slide, means to actuate said plunger to carry said stop down over said support and retract the same, and means, operating while said plunger is at and adjacent to the rear end of its travel, partially to rotate said plunger in opposite directions to raise and lower said stop.

23. In boxing mechanism, a slide provided with bearings, a support at the lower end of said slide, tracks also at the lower end of said slide, a plunger in said bearings, an arm secured to said plunger, a stop connected with said arm and having a lip which extends down back of said slide, and also having supports to ride on said tracks, means to actuate said plunger to carry said stop down over said support and retract the same, and means, operating while said plunger is at and adjacent to the rear end of its travel, partially to rotate said plunger in opposite directions to raise and lower said stop. 100

24. In boxing mechanism, a slide provided with bearings, a support at the lower end of said slide, tracks also at the lower end of said slide, a plunger in said bearings, an arm secured to said plunger, a stop connected with said arm and having a lip which extends down back of said slide, and also having supports to ride on said tracks, a frame, a shaft supported from said frame, cam members 110 mounted on said shaft, an arm pivotally connected with said frame and operated by one of said cam members, a link pivotally connecting said arm with said plunger, whereby said plunger is moved longitudinally, a sleeve mounted on said plunger between said bearings and keyed to the plunger to enable the same to move longitudinally in said sleeve, an arm extending from said sleeve, and a second lever pivotally connected with 115 said frame, operated by another of said cam members, and operatively connected with said arm, whereby said plunger is rocked. 120

25. In boxing mechanism, a slide provided with bearings, a plunger journaled in certain of said bearings and a rod journaled in certain others of said bearings, said rod being longer than said plunger, a pusher secured to said rod, dogs secured to the ends of said rod and extending into the path of 125 130

5 said plunger, and means to move said plunger in one direction into engagement with one of said dogs, and thereby move said rod and pusher in the same direction, and to move
10 said plunger in the opposite direction into engagement with the other of said dogs, and thereby move said rod and pusher in the opposite direction with the plunger.

26. In boxing mechanism, a slide provided
15 with bearings, a plunger journaled in certain of said bearings and a rod journaled in certain others of said bearings, said rod being longer than said plunger, a pusher secured to said rod, dogs secured to the ends of said rod and extending into the path of said plunger, a support, a shaft carried by said support, a cam on said shaft, a lever pivotally connected with said support, and operated by said cam, and a link pivotally connected with said lever and with said plunger, whereby said plunger is constantly reciprocated and said rod with said pusher is intermittently reciprocated.

27. In boxing mechanism, a slide provided
25 with bearings, a plunger slidably arranged in certain of said bearings, and a rod, longer than said plunger, slidably arranged in certain others of said bearings, said rod having dogs at the ends which extend into the paths
30 at opposite ends of said plunger, a pusher and a pin secured to said rod, a box holder having sides one of which is pivotally mounted and spring pressed, and has a finger in the path of said pin, and means constantly to reciprocate said plunger and thereby cause said rod to be intermittently reciprocated, through the medium of said dogs, whereby said pin actuates said side, through the medium of said finger, to remove the pressure from a box
35 in said holder, and said pusher moves said box rearwardly in said holder.

28. In boxing mechanism, a slide provided
45 with bearings, a plunger slidably arranged in certain of said bearings, and a rod, longer than said plunger, slidably arranged in certain others of said bearings, said rod having dogs at the ends which extend into the paths
50 at opposite ends of said plunger, an arm secured to said plunger, a stop connected with said arm and having a lip which extends down back of said slide, a pusher and a pin secured to said rod, a box holder having sides one of which is pivotally mounted and spring pressed, and has a finger in the path of said
55 pin, and means constantly to reciprocate said plunger and thereby cause said stop to be reciprocated, and said rod to be intermittently reciprocated, whereby said pin actuates said slide to remove the pressure from a box in
60 said holder, and said pusher moves said box rearwardly in said holder.

29. In boxing mechanism, a slide, a support at the lower end of said slide, an arm pivotally connected with said slide, a rocker having one end pivotally connected with said

slide and the other end rigidly attached to said arm, and provided at the top with a rigidly attached arm which extends rearwardly in the longitudinal direction of the machine, a gate secured to the free end of said last-named arm, and extending downwardly in position to rest on said support, and means intermittently to operate said rocker to raise and lower said gate. 70

30. In boxing mechanism, a slide, a support at the lower end of said slide, an arm pivotally connected with said slide, a rocker having one end pivotally connected with said slide and the other end rigidly attached to said arm, and provided at the top with a rigidly attached arm which extends rearwardly in the longitudinal direction of the machine, a gate secured to the free end of said last-named arm and extending downwardly in position to rest on said support, a frame, a shaft carried by said frame, a cam on said shaft, and a lever pivotally connected with said support, operated by said cam, and pivotally connected with said first-named arm, whereby said rocker is intermittently operated to raise and lower said gate. 75 80 85 90

31. In boxing mechanism, a slide provided with bearings, a support at the lower end of said slide, a plunger slidably arranged in said bearings, a sleeve keyed to said plunger, 95 an arm secured to said sleeve, a stop connected with said arm and having a lip which extends down back of said slide, an arm pivotally connected with said slide, a rocker having one end pivotally connected with said slide and the other end rigidly connected with said second-named arm, and provided on top with a rigidly attached arm which extends rearwardly in the longitudinal direction of the machine, a gate secured to said last-named arm and extending downwardly in position to rest on said support, cam-operated means to reciprocate said plunger and stop, cam-operated means to oscillate said plunger, sleeve, and stop, and cam-operated means to oscillate said rocker and raise and lower said gate. 100 105 110

32. In boxing mechanism, a slide, a support at the lower end of said slide, an arm, a pivotal connection for said slide arm, a box 115 holder mounted on the free end of said arm, and releasable means to support said holder at different operative positions relative to said support.

33. In boxing mechanism, a slide for sticks 120 of objects, a support at the lower end of said slide for said sticks, an arm, a pivotal connection for said arm, a box holder mounted on the free end of said arm adjacent to said slide, and releasable supporting means for said arm, whereby said holder is located in receiving position for sticks for said support, and can be moved down step by step a distance equal each time to the combined height of a row of sticks and a separator. 125 130

34. In boxing mechanism, a slide for sticks of objects, a support at the lower end of said slide for said sticks, means to control the movement of said sticks onto and on said support, an arm a pivotal connection for said arm, a box holder mounted on the free end of said arm, and releasable supporting means for said arm, whereby said holder is located in receiving position for sticks from said support, and can be moved down step by step a distance equal each time to the combined height of a row of sticks and a separator.

35. In boxing mechanism, a slide for sticks of objects, a support at the lower end of said slide for said sticks, means to control the movement of said sticks onto and on said support, an arm, a pivotal connection for said arm, a box holder mounted on the free end of said arm, releasable supporting means for said arm, whereby said holder is located in receiving position for sticks from said support, and can be moved down step by step a distance equal each time to the combined height of a row of sticks and a separator, a pusher to move a box backward in said holder to permit the sticks on said support to drop into said box, and cam-operated actuating means for said pusher.

36. In boxing mechanism, a slide for sticks of objects, a support at the lower end of said slide, means to control the movement of said sticks on said support, an arm, pivotal connection for said arm, a box holder mounted on the free end of said arm, and provided with a clamping member for a box in said holder, releasable supporting means for said arm, whereby said holder is located in receiving position for sticks from said support, and can be moved down step by step a distance equal each time to the height of a row of sticks and a separator, a pusher to move said box backward in said holder to permit said sticks to drop into said box, and cam-operated actuating means for said clamping member and said pusher.

37. In boxing mechanism, a slide provided with a dog, an arm, a pivotal connection for said arm, a box holder mounted on the free end of said arm, and a hand-operated lever pivotally connected with said arm, and having teeth to engage said dog and locate said holder at different receiving positions relative to said support.

38. In boxing mechanism, a slide provided with a stirrup and with a projection, an arm, a pivotal connection for said arm, and passing through said stirrup, whereby the downward movement of said arm is limited, a box holder mounted on the free end of said arm, and a hand-operated lever pivotally connected with said arm, and serrated to engage said projection and locate said holder at different receiving positions relative to said support.

39. In boxing mechanism, a pivotally mounted arm, a box holder mounted on the free end of said arm, said box holder having a fixed and a movable side, means to introduce sticks of points into said box while held between said sides, means to actuate said movable side to cause it momentarily to free said box, and means to move said box with its contents rearwardly while said movable side is in unclamped position.

40. In boxing mechanism, a slide for sticks of objects, a support at the lower end of said slide for said sticks, means to control the movement of said sticks onto and on said support, a box holder, means for supporting said holder in different operative positions relative to said support, whereby a box in said holder can be moved forward until the back side of the same contacts with the back edge of said support, and automatic means to move said box rearwardly in said holder, to permit the sticks on said support, against said back side of the box, to slide completely off of said support into the box.

CHARLES J. FANCHER.
ROBERT A. JOHNSON.
